UNITED STATES PATENT OFFICE.

ERNEST A. LOWE, OF PLAINFIELD, NEW JERSEY, ASSIGNOR, BY MESNE ASSIGNMENTS,
TO AUTOMATIC SPRINKLER COMPANY OF AMERICA, OF NEW YORK, N. Y., A COR-
PORATION OF NEW YORK.

AUTOMATIC RELEASING MECHANISM FOR FIRE DOORS.

1,404,534.

Specification of Letters Patent. Patented Jan. 24, 1922.

Application filed October 31, 1916. Serial No. 128,689.

To all whom it may concern:

Be it known that I, ERNEST A. LOWE, a citizen of the United States, and a resident of Plainfield, in the county of Union and State of New Jersey, have invented certain new and useful Improvements in Automatic Releasing Mechanism for Fire Doors, of which the following is a specification.

My present invention relates to automatic releasing mechanism adapted to bring about the closure or other movement of a door, window, shutter or the like, upon a change of temperature at an excessive or abnormal rate as in the case of fire or other condition accompanied by temperature changes and requiring the release of said door, window, shutter or the like.

In my prior applications for patent filed June 17, 1913 (patented June 11, 1918, No. 1,269,556), Serial No. 774,101, and May 12, 20 1915 (patented Dec. 12, 1916, No. 1,208,177), Serial No. 27,485, allowed May 15th, 1916, I have described devices of this general character wherein the releasing mechanism 25 is under the control of a thermostat acting to free the same only when the temperature rises at an abnormal rate and the use in connection with said devices of the old form of release effected by means of a fuse 30 or fixed temperature device directly connected to the door or the cord or rope by which the same is held in normal position and acting, on fusion, to free the door.

My present invention consists in the construction of the releasing mechanism whereby said fixed temperature device may be incorporated therein as a part of the construction to be applied to the door in place and the invention will be hereinafter described in connection with that particular construction of apparatus which forms the subject of my application filed May 12th, 40 1915, as an improvement upon the invention covered by the first of the applications above mentioned.

My invention further consists in certain improvements in the details of construction of the rate of rise temperature device and which are described but not claimed in the 50 aforesaid applications for patent.

In the following description the fuse or other device which controls the operation of the door and which operates on the attainment of a fixed or absolute temperature,

will be hereinafter referred to as the fixed 55 temperature control thermostat and the device which responds only to a rate of rise greater than that allowable with safety under the particular conditions of use will be referred to as the rate of rise thermostat. 60 In addition to these thermostats and used in combination with them to effect the desired result, the apparatus described in the latter of the two above applications and in which I have shown my present invention 65 embodied comprises, briefly stated, a release device immediately associated with the door and which acts to free the door by freeing the same from the influence of any restraining device, as for instance a weight or 70 counterweight opposing the continual bias of a spring or weight tending constantly to move the door, detent mechanism normally holding said release device out of action and comprising preferably a train of detent 75 mechanisms having a self-releasing tendency in their members as described in my application filed May 12th, 1915, and a final releasing dog or detent subject to the actuation or control of the rate of rise thermostat. 80

In the accompanying drawings, Fig. 1 is a front elevation of a form of apparatus in which my invention is embodied.

Fig. 2 shows a self-closing fire door equipped for use in connection with my invention.

Fig. 3 is an inverted plan, parts being shown in horizontal section.

Fig. 4 is an edge view, the casing being shown in section.

Fig. 5 is an elevation of a portion of the detent mechanism detached from the other parts.

Fig. 6 shows in detail one of the elements of the detent mechanism.

Fig. 7 is a vertical section on the line c-c Fig. 4.

1 is the framework in which the shafts of the detent mechanism are mounted and 1' is the casing therefor. 2 is the release 100 arm of the release device which is adapted to free the door or similar part by turning down around the center 3 into the position shown in Fig. 5, so as to slip the cord or weight-sustaining device 2' of the counterweight 6 by which the door 7 is normally held in the position shown. The center 3 may be a reduced end of a rock shaft of

the mechanism and the arm may be loosely hung thereon as indicated. Upon the release of the detaining counterweight the door moves by gravity on its tracks to close 5 the opening as shown. A fixed temperature control thermostat 7 comprising a fusible link is shown at its usual location included in the counterweight sustaining cord or connection between the same and its 10 fixed point of attachment. The detent mechanism by which the release device 2 is normally held in position shown in Fig. 1 comprises a train of detents which, to the extent to be indicated, have a tendency to 15 release themselves.

Briefly, the train shown comprises first (in the order of proximity to said release device 2) detent arm 9 extending from weighted rock shaft 3 and connected with 20 the release device 2 as will be presently described. Arm 9 normally stands detained by engagement with a shoulder 11 on a detent arm 12 projecting from rock shaft 13. Detent arm 12 normally stands engaged and 25 locked by weighted rock shaft 14 or part 14 thereon cut away, as shown, so that when the shaft turns the detent arm 12 will be released. The detent arm 15 carried by said weighted rock shaft is provided with 30 the detent latch 16 adapted to lock against the shoulder 17 on the rock shaft provided with detent arm 18. The latch 16 passes the projection of the shoulder 17 and latches against the same when the rock shaft is 35 returned to normal position by the operation of the link 20 carried by an arm 40 projecting from the shaft 13 having the re-setting handle 21. The detent arm 18 is locked by a detent not having self-releasing 40 tendency but positively locking the same and subjected to the actuation or control of the rate of rise thermostat directly or indirectly. It is positively locked by the dog 22 on a latch arm 23 and the latter is held 45 positively from movement in a direction to free the detent arm 18 by means of the latch or catch 24. The latter in turn is positively operated by the power of the rate of rise thermostat. It is re-set by hook 41 on arm 50 40. The rate of rise thermostat, in its preferred form, comprises the following parts: 55

25 indicates a metallic chamber the walls of which may be corrugated as shown and which is preferably made of metal to readily conduct heat to the liquid or fluid contents of the same. The air or fluid space of said container communicates by a pipe 26 with a confined space at the back of a diaphragm 27 clamped in suitable disks and having a 60 pin engaging the end of the detent lever 24 as shown. The forces of expansion of the contents of container 25 and connected piping and spaces are employed as a means for operating the detent 24 by acting against 65 the resilient diaphragm 27. The operation

of said detent takes place when the rise of temperature affecting the thermostat is at an abnormal rate or rate greater than the rate of ordinary rise accompanying changes of atmospheric temperature or other changes 70 permissible under the conditions or in the situation of use of the device. To cause the action upon the detent 24 to take place only when the rate of rise is abnormal, an air vent or leak is provided in connection with 75 the space in which the heated expansible air or gas is contained and said air vent is adjusted to allow the escape of air under ordinary or normal rates of temperature change at such a rate as to preserve a practical 80 equilibrium of the forces acting on opposite sides of the diaphragm 27. This air vent may be mounted in an extension 28 from the air chamber. The end of said extension is provided with a detachable screw 85 cap 29 sealing the end of the extension and carrying the vent pipe 30 the inner end of which projects into the air space.

Within said pipe is air filtering material as indicated at 31 and consisting preferably 90 of fibrous material such as threads or filaments. The inner end of this vent tube is constricted or compressed to secure the desired minute venting action which determines at what rate of rise of temperature the 95 thermostat shall become operative to release the detent mechanism.

The air chamber may, for mechanical protection, be enclosed in a suitable protecting cage 32. A rate of rise of temperature 100 greater than normal or permissible rate consistent with safety or required conditions of use, causes an accumulation of pressure behind the diaphragm 27 and hence a mechanical operation of the catch 24 which in 105 turn operates catch 22 and frees the detent train described, thus freeing the release 2 and causing the door to close.

The fixed temperature release device which is employed as part of the same self-contained release mechanism and is designed to operate upon any great or excessive and sudden change of temperature is incorporated in the release mechanism between the release device 2 and the same at any desired 110 point but preferably directly between the release device 2 and the next succeeding member. Thus, as shown, said fixed temperature control thermostat comprising a fusible link 33 may be secured at one end to 115 a screw or pin 34 on the release device 2 and at its opposite end may be similarly fastened to the arm 10 extending from the rock shaft 3 carrying detent arm 9 of the 120 detent mechanism. The release device being thus connected with the detent mechanism, will be normally held from turning. Said fixed temperature control thermostat will however release the door by freeing the 125 release device 2 should temperature con- 130

ditions be such as to fuse the said link 33. At the same time, so long as the link remains intact, the release device 2 will be sustained in normal position but the mechanism will be free to operate and release the device 2 under the control or action of the rate of rise thermostat when a temperature change takes place insufficient nevertheless to fuse the link, said release under the action 10 of the rate of rise thermostat taking place as already described by the action of the train of detents connected through the detent arm 9, arm 10 and link 33 with release device 2.

15 What I claim as my invention is:

1. An automatic release apparatus of the character described having a dual control by two thermostats, one a rate of rise thermostat controlling a release device through a 20 detent mechanism and the other a fixed temperature thermostat, said fixed temperature thermostat being incorporated therein to form a mechanical link in the mechanical connection between said detent mechanism and the release device.

2. A releasing mechanism of the character described for fire doors and the like having a dual control of the door by two thermostats, one a rate of rise thermostat controlling a release device through a detent mechanism, the other a fixed temperature thermostat consisting of a fusible link, said fusible link constituting the fixed temperature element of the device being incorporated therein to form a mechanical connection between the detent mechanism and the release device.

3. A thermostatically controlled release mechanism having a release device and detent mechanism governing the action of said 40 release device, and having a fusible link incorporated in the apparatus as a mechanical connection between the detent mechanism and the release device whereby said detent mechanism may act mechanically through 45 the link to hold the release device against operation and said fusible link may at any time act to free the release device without operation of the detent mechanism.

4. In a releasing mechanism for fire doors 50 and the like, provided with a release device, a detent mechanism, a rate of rise thermostat, and a catch for the detent mechanism actuated by the force of expansion of said rate of rise device, a fixed temperature control thermostat incorporated in and forming a component part of the mechanical con-

nexion between the detent mechanism and the release device.

5. In a rate of rise thermostat having a sealed air container and a detent actuating 60 diaphragm operated by the forces of expansion of the confined air, an air vent connected to the confined air spaces and comprising a pipe constructed to secure the desired minute venting action and containing 65 air filtering material.

6. In a rate of rise thermostat having a sealed air container and a detent actuating diaphragm operated by the forces of expansion of the confined air, an air vent comprising 70 a pipe extending into the air space and having a constricted passage way containing air filtering material.

7. In a rate of rise thermostat having a sealed air container and a detent actuating 75 diaphragm operated by the forces of expansion of the confined air, an air vent comprising a pipe extending into the air space and secured to a detachable cap mounted on an air outlet or extension.

8. A rate of rise thermostat comprising an air chamber having a body of confined air, a cap adapted to seal an outlet in said chamber and a pipe carried by said cap and extending into the air space, said pipe being 85 provided with filtering material and being adapted to limit the escape of air when heated to a predetermined rate.

9. A rate of rise thermostat comprising a metallic container having an air vent direct 90 to the atmosphere adapted to allow leakage of air at a predetermined rate, a detent actuating diaphragm and a pipe connecting the space behind the diaphragm with the air space of the container.

10. A detent controlled releasing mechanism for fire doors comprising a rock lever, a connected rock shaft and a release arm loosely pivoted to said rock shaft, and a rate of rise thermostat controlling said releasing 100 mechanism, a fusible link releasably connecting said release arm to said rock lever to independently release said arm when a predetermined temperature is reached.

Signed at Youngstown, in the county of 105 Mahoning and State of Ohio, this 27th day of October, A. D. 1916.
